UNITED STATES PATENT OFFICE.

SANDFORD C. COX, OF BROOKLINE, MASSACHUSETTS, ASSIGNOR TO COX MULTI-MAILER COMPANY, OF AUGUSTA, MAINE, A CORPORATION OF MAINE.

PRINTING OR ADDRESSING MACHINE.

1,075,965.

Specification of Letters Patent.

Patented Oct. 14, 1913.

Application filed December 2, 1907. Serial No. 404,779.

To all whom it may concern:

Be it known that I, SANDFORD C. Cox, a citizen of the United States, residing at Brookline, in the county of Norfolk and State of Massachusetts, have invented certain new and useful Improvements in Printing or Addressing Machines, of which the following is a full, clear, and exact specification.

- 16 This invention relates more particularly to that class of printing or addressing machines, appropriate for printing the name and address and other matter upon newspapers, magazines, and other like articles, 15 or upon their wrappers, and of this class it has more especial reference to the machines which are designed for using slugs or linotypes which bear the name and address.
- 20 The invention has for its primary object to provide improved and simple means whereby the slugs or linotypes may be extracted one at a time from a supply of these slugs and placed in printing position ready 25 to produce an impression upon the paper or other article, regardless of whether the slug extracted be a single line or a plural line slug; the invention having for its further object to remove the slugs automatically 30 from the printing position and again store them in their former regular order ready for repeated use.

With a view to the attainment of these ends and the accomplishment of certain 35 other objects which will hereinafter appear, the invention consists in the features of novelty which will now be described with reference to the accompanying drawings, and more particularly pointed out in the 40 claims.

In the said drawings—Figure 1 is a plan view of a printing or addressing machine embodying this invention, partly broken away and with the platen removed. Fig. 2 is a side elevation thereof, partly in vertical, longitudinal section. Fig. 3 is a similar view of the opposite side of the machine. Fig. 4 is an enlarged detail longitudinal sectional view taken on the line 4—4 of 45 Fig. 1. Fig. 5 is a perspective view of one of the slugs. Fig. 6 is a similar view of another one of the slugs of a different form. Fig. 7 is a detail plan section of the slug retainers hereinafter described, taken on the 50 line 7—7 of Fig. 8. Fig. 8 is a vertical

section thereof, taken on the line 8—8 of Fig. 7. Fig. 9 is a detail vertical section of one of the slug holding dogs in the dead galley hereinafter described, taken on the line 9—9 of Fig. 10. Fig. 10 is a plan section thereof on the line 10—10 of Fig. 9. Fig. 11 is a detail perspective view of the feeding and ejecting plunger. Fig. 1^a is an enlarged detail plan view of one of the switches hereinafter described. Fig. 6^a is a detail perspective view of a certain modification hereinafter explained.

In a printing or addressing machine of this character, it is desirable to employ means whereby the letters and characters constituting the name and address of each 70 addressee may be held together in the form of a single object or element, such as a slug or linotype, although it is not essential that they be cast in a single piece like the 75 ordinary slug or linotype. In a co-pending application filed September 12, 1907, Serial No. 392,432, I have shown, described and claimed for use in addressing machines of this character, a box or holder whereby the 80 ordinary types bearing the letters and characters of the name and address of each addressee may be held or carried separately from the others. In Figs. 5 and 6 of the drawings of this application are shown two 85 different forms of slugs or linotypes, one being a plain slug and the other being a slug having a notch for the purpose which will be hereinafter described, and in Fig. 6^a is shown one of these boxes or type-holders, 90 constituting the subject matter of the claims in the other application. With the present machine I prefer, however, to employ the slugs, and have illustrated the same in connection with the various parts of the machine. 95 These may be cast in one, two, three, and even a greater number of lines, according to the amount of matter to be printed in connection with the name of each addressee. The single line slugs bearing 100 such matter may be cemented or riveted together in the form of a single printing or type element, and in this specification the term "type-element" will be employed as a generic designation of any element bearing 105 or carrying the characters to be printed from.

The type-elements to be printed from, indicated at 1, are stored in a horizontal or substantially horizontal race or galley 2, 110

and in this galley they are arranged contiguous to one another with their printing faces uppermost. Any suitable means may be employed for feeding the supply of slugs or printing elements forward in the galley 2, such, for example, as a continuously, or substantially continuously moving belt or band 3, whose upper run lies upon the bottom of the galley 2 and forms a support for the type-elements 1, and consequently feeds them forward by frictional contact with the entire supply as soon as the type-element at the end of the supply is removed. This belt or band may be caused to travel in the proper feeding direction by any suitable means, the details of which are not material to this invention. In the drawings I have shown one end of the band passing over an idler 4, and the other end over a driving pulley 5, which is provided at one end with a ratchet wheel 6, arranged to be engaged by a pawl 7 on lever 8, whose lower end engages in a cam groove 9 formed in cam 10. This cam is secured to a shaft 11 driven by bevel gears 12, 13 from some moving part of the driving mechanism, or from any suitable source of power not necessary to describe. The feeding action of the belt or band 3 maintains the foremost slug or type-element against the end wall 14 of the feed galley or race 2, and formed in the side wall of the race or galley 2 flush with the end wall 14, that is to say, with one of its walls in the same vertical plane as the end wall 14, is a slot or passage 15 which is as wide as the thickness of the widest one of the type-elements 1. In this example of the invention it is shown equal in width to a treble line slug, but it will of course be understood that where the boxes or carriers for single types shown in Fig. 6^a of the drawing are employed, this slot or passage 15 will be at least as wide as the widest one of these boxes or carriers, and directly in line with the slot or passage 15 and in the same vertical plane as said slot or passage is a slot, shoulder or seat 16 formed in the upper end of a plunger 17. This slot or seat 16 is the same in width as the slot 15 and constitutes a continuation thereof, so as to receive any one of the slugs or printing elements that may be projected through the slot 15 from the feed galley 2, but in order that the printing elements or slugs of various thicknesses may all be retained securely in their upright printing position against that wall of the slot or slug-seat 16 which is flush with the wall 14, the opposite wall of the slug-seat 16 is provided with springs 18 which are of leaf form and curve in a direction away from the slot 15 to permit the slugs or printing elements to be readily inserted into the slug-seat while serving to hold any slug securely against the opposite wall. These

springs are of course let into the wall of the slug-seat as indicated in Figs. 1 and 4 of the drawings, to permit of sufficient deflection when a slug of the maximum thickness is introduced.

The slugs are introduced into the slug-seat 16 of the plunger 17 by being pushed endwise, and this is accomplished by a plunger which extends crosswise of the end of the feed galley 2, and serves not only to advance a slug or type-element from the feed galley 2, but also to eject the old slug from the slug-seat 16. This plunger is shown in perspective in Fig. 11, and may consist of a body or bar 19 having two lugs 20, 21 projecting from the side thereof. The plunger lies in a guide-way 22 formed in a block 23 extending entirely across the end of the galley 2, and in fact, forming the end wall 14 thereof, and also across one face of the plunger 17 and forming one of the guide walls for the plunger 17. The top of the guide way 22 may be closed by a plate 24 which holds the plunger body 19 down in place while permitting of its necessary longitudinal and lateral motion. The under side of the body 19 is provided with pins 25, 26, and the bottom of the guide way 22 is provided with guide grooves 27, 28, which are connected together at both ends by oblique guide grooves 29, 30, and at an intermediate point by an oblique guide way 31, which is parallel with the grooves or guides 29, 30. As the plunger body rests upon the bottom of the guide way 22, the pins 25, 26 thereon project downwardly into one or the other of the guide grooves 27, 28. When situated in the guide groove 27, the lugs 20, 21 project over the outer face of the end wall 14 a sufficient distance to engage the end of the foremost slug or printing element 1, but not far enough to engage the next type-element, even though the foremost one be but a single line slug or element, and the lug 21 of the plunger similarly engages with the end of the slug or type-element in the slug-seat 16, as clearly shown in Fig. 1. When the plunger body 19 is now moved forward or toward the slug-seat 16, it will be seen that the foremost slug in the feed galley 2 will be advanced from the feed galley through the slot 15 and into the slug-seat 16 of the plunger 17, while at the same time the slug or printing element, whether it be a single or a plural line slug, in the seat 16, will be ejected or pushed endwise therefrom by the time the lug 20 moves far enough to place the new slug entirely upon the seat 16. When the plunger body 19, with its lugs 20, 21, makes its return movement, it is also moved laterally so as to withdraw the lugs 20, 21 from the vertical plane of the end wall 14 and slug-seat 16. As a means for accomplishing this, the guide groove 27 is provided adjacent the guide ways 29, 31, with two

switches 32, 33, which are held normally across the guide groove 27 by any suitable yielding means, such as springs, an example of one of which is shown at 34 in Fig. 1^a, 5 so as to permit the pins 25, 26 to pass the switches and to cause the switches to thereafter spring back into place and prevent the pins 25, 26 from returning in the same groove 27, but compelling them to be deflected 10 into the oblique guide ways 29, 31, and eventually enter the groove 28, thereby withdrawing the lugs 20, 21 out of the way of the slugs until the plunger has about completed its return movement. As the pins 25, 15 26 are about to arrive at the end of their return stroke in the groove 28, they encounter two additional switches 35, 36 respectively, which are arranged adjacent the guide ways 31, 30 respectively; in fact, the guide way 20 31 is constituted on both sides by the switches 32 and 35. These switches 35, 36 are held normally across the guide groove 28, like the switch 33, by suitable springs 37, so as to permit the pins 25, 26 to pass 25 and enter the guide ways 30, 31 by the time the plunger reaches the end of its return stroke. As the plunger again moves in the direction of its feeding stroke, it is carried laterally by the guide ways 30, 31, and by 30 the time the lug 20 reaches the end of the foremost slug in the galley 2, the plunger will be sufficiently deflected toward the slug to bring the lugs 20, 21 into engagement with the slugs in the galley 2 and the slug 35 seat 16, ready to feed another slug into the slug-seat and to eject the old slug from the slug-seat. The plunger body 19 may be given its described reciprocating motion from any suitable moving part of the machine. 40 There is shown for this purpose a crank 38 arranged on the upper end of a shaft 39, which is driven by bevel gear 40 engaging bevel gear 41 on a shaft 42 extending across the machine and driven from any 45 suitable moving part or other source of power. The crank 38 is connected by link 43 with an ear 44 on the end of the plunger body 19.

It is apparent that the lug 20 in advancing a single line slug or type-element from 50 the galley 2 into the slug seat 16, might, under some circumstances, cause the next slug or element to also move endwise into the seat 16, or to be partially displaced by 55 frictional contact with the end slug. In order, therefore, that this may be prevented, the slot 15 is provided with yielding slug retainers 45, 46, or any other means which will apply more resistance to the end of the 60 slugs to be retained in the galley 2, while the end one is being fed therefrom, than the force incident to the friction between the end slug, and those to be retained. These 65 retainers 45, 46, are in the form of longitudinally movable blocks which project

transversely of the slot 15, one slightly in advance of the other. They need not project entirely across the slot 15, and in fact, it is preferable to leave at the end of the foremost one sufficient space for the end 70 slug to pass through without resistance. The sides or edges of these retainers which are presented to the ends of the slugs in the galley 2 are beveled to permit a slug greater in thickness than a single line slug to pass, 75 when receiving the full pressure of the lug 20, while at the same time introducing sufficient friction against the slugs not engaged by the lug 20 to prevent them from following the end slug through the passage 15. 80 It is quite apparent that the only advantage in employing a plurality of these retainers 45, 46, instead of a single one, is that the bevel face of each might be too abrupt and afford such excessive resistance or friction 85 against the end of a plural line slug being ejected by the lug 20 as to cause damage or excessive wear to the parts. The retainers 45, 46 are held in place in the side wall of the galley by pins 47 passing through slots 48 90 in the retainers, and the retainers are pressed yieldingly into the slug passage 15 by springs 49 arranged at their inner ends.

It may be understood from the foregoing description that the impression is produced 95 while the slug or printing element rests in the slug-seat 16 of the plunger 17. This is preferably effected by lifting the plunger 17 until the paper or article to be printed upon, indicated at 50, Fig. 4, is engaged by 100 the printing surface of the slug, rather than depressing the article 50 against said printing surface, a platen 51 being arranged over the plunger 17. This rising movement of the plunger 17 is produced in any suitable 105 way, as for example, a cam or tappet 52 secured to the shaft 42 in position to engage the lower end of the plunger at each revolution of the shaft. When the cam or tappet 52 passes, the plunger is returned by a 110 spring 53 or other suitable means interposed between a projection 54 on the plunger and the under side of a wall 55 arranged parallel with the block 23 and constituting one 115 side of the guide way in which the plunger 17 works.

56 is a stop for limiting the downward movement of the plunger 17.

The rotary movement of the cam 52 is of course so timed with relation to the movement of the crank 38 that the impression plunger 17 will make its upward stroke after the feeding and ejecting plunger 19 has made its forward or feeding stroke and has partially returned to withdraw the lugs 20, 21 from the path of movement of the plunger 17. The papers or articles 50 to be printed upon are in the meanwhile automatically advanced to the proper position under the platen 51 by mechanism suitably 120 125 130

timed with relation to the movement of the plunger 17, or of course they might be placed over the plunger by hand, if desired, but ordinarily they would be fed into position automatically by suitable feed tapes 57, 58, similar to the feed tapes ordinarily employed in the printing press art for feeding the paper to the printing position. After the slug or type-element has produced 10 the impression and the plunger 17 has returned to its lower position, the slug is ejected endwise through a passage 59 into what may be termed a dead galley, whose side walls are shown at 60, 61, this endwise 15 movement of the slug, as before explained, being produced by the lug 21. As the slug moves through the passage 59, it engages a spring 62, which presses it forward in the dead galley to a position against two beveled yielding dogs 63, where it is held until it is engaged from the rear by a plunger 20 64 which pushes it farther into the dead galley past the dog 63, the latter yielding to permit the slug to pass and then springing back into place to hold it against retrograde movement against the slugs that have been previously placed in the dead galley. This plunger 64 may be reciprocated horizontally in time with the balance of the 25 mechanism by a cam 65 having a cam groove 66 in which engages a stud 67 on the bottom of the plunger 64, the cam groove being so formed as to cause the plunger 64 to move forward and back after a slug or printing element has been pushed endwise into the 30 dead galley by the lug 21, and then to remain at rest until another slug has been thus ejected into the dead galley. In order that the plunger 64 may pass the dog 63, its 35 forward corners are notched, as shown at 68. The spring 62 may be carried on the forward face of the plunger 64, or on any other suitable support.

With addressing machines employed for 40 addressing newspapers, periodicals and the like, it is desirable, for the sake of saving room in the galleys, to print the name of the town or locality on but one of the various papers or periodicals going to that 45 point or locality, the entire page or series being usually bundled together when shipped or mailed. This make it desirable, therefore, to provide means for readily determining in the newspaper office just where 50 the page or series belonging to one town leaves off, and those belonging to another town commence. Consequently the machine is provided with means for printing a distinguishing mark, which may be more 55 readily observed than the name of the town, upon either the first or the last of the series 60 going to each town. This mark may be simply a daub or spot, which may be produced by a inked stamper 69, arranged to 65 engage the paper as it is held by the tapes

57, 58, or at any other suitable place or time. This stamper or marker is automatically actuated or thrown into action by the slugs or type-elements themselves, which have a certain relation in the feed galley, and this 70 relation is maintained each time the slugs pass through the machine. One of the slugs or type-elements belonging to each town or series may be notched, as shown at 70, or otherwise differently proportioned from 75 the others, or, if desired, all of the slugs or type-elements excepting one of them in each town or series may be notched, so that when the unnotched slug comes into engagement with a finger 71, the finger will be thrown 80 outwardly and engage with suitable connections for actuating the stamper 69. In this example of the invention, the finger is shown projecting through the side wall 61 of the dead galley, and is formed on a lever 72 arranged to engage a pin 73 on bell crank 74, and this bell crank is arranged to engage a 85 crank arm 75 on a shaft 76, which carries an arm 77 supporting the stamper 69, so that each time an unnotched slug passes the finger 90 71, the stamper will be thrown against the paper. This finger 71 must be so positioned, of course, that when either the first or the last paper belonging to a series arrives at the stamper, the unnotched slug will be 95 ready to engage the finger 71. Hence the unnotched slug must bear a certain relation in the order of arrangement of the lugs in the galley to the slug which prints either the first or the last address of the series. 100

In order that the invention may be understood by those skilled in the art, the details of an exemplification thereof have been thus specifically described, but

What I claim is:

1. In a machine for the purpose described the combination of a galley for holding a supply of printing elements, means for ejecting the printing elements as required transversely from the galley, an impression plunger for elevating the printing elements directly they are ejected to a printing position, operatively connected with said ejecting means, and means also operatively connected with the said ejecting means for removing the printing elements from the said plunger at the conclusion of the impression. 105

2. In a machine for the purpose described the combination of a galley for holding a supply of printing elements, a galley for receiving the printing elements after they have been printed from, a lifting plunger arranged between said galleys for lifting a printing element into printing position, and ejecting means for simultaneously ejecting a 110 printing element from the first said galley upon said plunger and from the plunger into said receiving galley. 115

3. In a machine for the purpose described the combination of a galley for storing a 120

supply of printing elements, a second galley for receiving the printing elements after they are printed from, ejecting means for engaging and ejecting a printing element from the first said galley to a printing position intermediate the two galleys and at the same time engaging and removing a printing element from the printing position to the said receiving galley and from the space into which the first said element is directly positioned from the supply galley, and means for producing an impression from the printing element while in said printing position.

4. In a machine for the purpose described the combination of a galley for containing a supply of printing elements, a receiving galley for receiving the printing elements after they have been printed from, said receiving galley being spaced from the first said galley to provide a printing position for the printing elements between them, an ejecting means having two lugs adapted to engage a printing element in the first said galley and a printing element at said printing position for simultaneously moving a printing element into the printing position and a printing element from the printing position into the receiving galley, and means for moving said ejecting means to cause said lugs to engage the printing elements when moving in one direction and to move out of the line of the printing elements when returning.

5. In a machine for the purpose described the combination of a galley for containing a supply of printing elements, a galley for receiving the printing elements after they have been printed from, spaced from the first said galley to afford a printing position between them, an ejector having means for simultaneously engaging a printing element in the first said galley and a printing element in the said printing position, means for moving said ejector in one direction to cause it to push the printing elements endwise, and means for shifting the ejector to move the same out of the line of the printing elements when moving in the opposite direction.

6. In a machine for the purpose described the combination of a galley for containing a supply of printing elements, a second galley for receiving the printing elements after they have been printed from, spaced from the first said galley to provide a printing position for the printing elements between them, an ejector having two lugs for simultaneously engaging a printing element in the first said galley and one in said printing position, two tracks or ways for guiding said ejector, and switches operatively related to said tracks for switching the ejector from one track to the other when making its return movement.

7. In a machine for the purpose described the combination of a galley for holding a supply of printing elements, a second galley for receiving the printing elements after they have been printed from, spaced from the first said galley to afford a printing position for the printing elements between the galleys, said machine embodying a passage for the printing elements from the first said galley to said printing position, yielding dogs guarding the said passage for preventing accidental movement of the printing elements therethrough, means for ejecting the printing elements from the first said galley through said passage against the resistance of said dogs and lodging them in said printing position, and means for producing an impression from the printing elements while in said printing position.

8. In a machine for the purpose described the combination of a galley for a supply of printing elements, a second galley for receiving the printing elements after they are printed from, spaced from the first galley to afford a printing position for the printing elements between them, said machine embodying passages for the printing elements from the first galley to said printing position and from the printing position to the second galley, yielding dogs guarding said passages for preventing accidental movement of a printing element therethrough, means for ejecting a printing element from the first galley to said printing position and from the printing position to the second galley, and means for producing an impression from the printing elements in said printing position.

9. In a machine for the purpose described the combination of a galley for a supply of printing elements, a second galley for receiving said elements after they are printed from, spaced from the first said galley to afford a printing position for the printing elements between them, means for engaging and forcing said elements from the first said galley to said printing position and for engaging and forcing said elements from the printing position into the receiving galley simultaneously, a pusher in the receiving galley for advancing the printing elements therewith, dogs for holding the printing elements in the receiving galley against retrograde movement, and means for shifting the printing element for producing an impression therefrom while in said printing position.

10. In a machine for the purpose described the combination of a galley for a supply of printing elements, a second galley for receiving the printing elements after they are printed from, means for producing an impression from the printing elements, means for ejecting the printing elements into the receiving galley, a pusher in the re-

ceiving galley for advancing the printing elements therealong, a projection extending into the receiving galley, said printing elements being differently proportioned whereby some of them will engage and deflect said projection, as the printing elements are pushed along the receiving galley, and a marking means operatively connected with said projection for producing a mark upon 10 a paper when said projection is thus actuated.

11. In a machine for the purpose described the combination of a galley for a supply of printing elements, a second galley 15 for receiving the printing elements after they are printed from, a reciprocating impression plunger arranged to receive the printing elements from the first said galley, having a seat for the printing elements, 20 means for simultaneously engaging a printing element in the first said galley and a printing element on said plunger for ejecting the printing element from the plunger into the receiving galley and a printing element from the supply galley on to the plunger, and means operatively connecting said plunger with said ejecting means.

12. In a machine for the purpose described the combination of a galley for a supply of printing elements, a receiving galley for the printing elements after they are printed from, a reciprocating impression plunger having a seat for the printing elements arranged to receive them endwise 35 from the first said galley, a spring on said impression plunger for holding the printing elements in place thereon, and means for simultaneously ejecting a printing element from the first said galley into said seat and a printing element from said seat into the 40 second said galley.

13. In a machine for the purpose described, the combination of a galley for holding a supply of printing elements, means 45 for ejecting the printing elements as required transversely from the galley, and a reciprocating impression plunger for receiving and elevating the printing elements thus ejected to a printing position, operatively connected with the said ejecting means, said ejecting means also serving to remove the printing elements from the said plunger at the conclusion of the impression.

14. In a machine of the class described, 55 the combination of a galley for holding a supply of printing elements, a plunger for receiving one of said elements and moving the same into a printing position, means for retaining the said printing element against displacement with respect to the plunger, said means including a yielding element movable with the plunger and adapted to engage the printing element, and means for ejecting the printing element against the

tension of the said yielding element after 65 being printed from.

15. In a machine of the class described, the combination of a galley for holding a supply of printing elements, a plunger for receiving one of said elements and moving 70 the same into a printing position, means for feeding the elements into a position to be engaged and moved by the plunger, means for retaining the said element on the plunger whereby the element may be moved into 75 and out of printing position thereby, and means for ejecting the said element transversely from the plunger and with respect to the supply after being printed from.

16. In a machine of the class described, 80 the combination of a galley for holding a supply of printing elements, a reciprocating plunger for receiving one of said elements and elevating it into a printing position, means for feeding said elements to 85 the plunger, a yielding device for holding the next adjacent printing element from displacement when one of said elements is removed, and means for ejecting directly from the plunger the element received by the 90 plunger and in a direction, transversely of the plunger, after being printed from.

17. In a machine of the class described, the combination of a galley for holding a supply of printing elements, a plunger for 95 receiving one of said elements and moving it into a printing position, yielding means for holding the next adjacent element against displacement when one of the elements is removed, means for feeding said 100 elements to the plunger, means for retaining an element for movement with the plunger including a yielding member for holding the element against transverse movement with respect to the plunger, and means for 105 ejecting said element transversely of the plunger after being printed from.

18. In a machine of the class described, the combination of a galley for holding a supply of printing elements, a plunger for 110 receiving one of the elements and moving it into a printing position, means for successively feeding the elements to the plunger, means for retaining one of the elements for movement with the plunger, and an ejector 115 movable transversely of the plunger and adapted to engage and eject the element from the plunger against the tension of the retaining means and after being printed from.

19. In a machine of the class described, the combination of a galley for holding a supply of printing elements, a plunger for receiving one of the elements and moving it into a printing position, means for feeding the elements to the plunger, means for holding the element against displacement 125 with respect to the plunger, a receiving

galley, means for ejecting the printing element against the tension of the holding means transversely of the plunger into the receiving galley after being printed from, 5 and means for advancing the elements in the receiving galley.

20. In a machine of the class described, the combination of a galley for holding a supply of printing elements of different 10 thicknesses, a plunger for successively receiving the elements and moving them into printing position, yielding means for holding the element against displacement with relation to the plunger, a receiving galley 15 adjacent and having a passage communicating with the supply galley, a yielding element extending into the passage and adapted to be engaged and deflected by some of the printing elements when they are moved 20 through the passage and into the receiving galley, and means for moving the printing elements into the receiving galley after they have been printed from.

21. In a machine of the class described, 25 the combination of a galley for holding a supply of printing elements of different thicknesses, a plunger for successively receiving the elements and moving them into printing position, yielding means for holding the elements against displacement with relation to the plunger, a receiving galley 30 adjacent and having a passage communicating with the supply galley, a yielding element extending into the passage trans- 35 versely of the line of movement of the element therethrough and adapted to be engaged and deflected by some of the printing elements when they are moved through the passage and into the receiving galley, and 40 means for moving the printing elements into the receiving galley after they have been printed from.

22. In a machine of the class described, the combination of a galley for holding a 45 supply of printing elements of different thicknesses, a plunger for successively receiving the elements and moving them into a printing position, said plunger being provided with a shoulder adapted to receive the 50 elements, means for feeding the elements onto the shoulder, means for holding the elements in position thereon, a receiving gal-

ley having a passage communicating with the supply galley, a yielding member extending into the passage and transversely 55 of the line of movement of the printing elements therethrough and adapted to be engaged and deflected by some of the elements, and means for moving the elements from the plunger and through the passage 60 into the receiving galley after they have been printed from.

23. In a machine of the class described, the combination of a galley for holding a supply of printing elements of different 65 thicknesses, a plunger for successively receiving the elements and moving them into a printing position, said plunger being provided with a shoulder adapted to receive the elements, means for feeding the elements 70 onto the shoulder, means for holding the elements in position thereon, a receiving galley having a passage communicating with the supply galley, a yielding member extending into the passage and transversely of 75 the line of movement of the printing elements therethrough and adapted to be engaged and deflected by some of said elements, means for moving the elements from the plunger and through the passage into the 80 receiving galley after they have been printed from, and means for advancing the elements in the receiving galley.

24. In a machine of the class described, the combination of a galley for holding a 85 supply of printing elements, a plunger for successively receiving the elements and moving them into a printing position, means for feeding the elements to the plunger, an 90 ejector for ejecting the elements after being printed from, means for operating the ejector, a marker adapted to place a mark upon one of the papers, and means controlled by some of the printing elements for operating the marker. 95

In testimony whereof I have signed my name to this specification, in the presence of two subscribing witnesses, on this 23rd day of November, A. D. 1907.

SANFORD C. COX.
